FLUID MOTOR

Wade H. Wineman, Coelspring Township, La
Porte County, Ind., assignor to Sullivan Ma-
chinery Company, a corporation of Massa-
chusetts

Application September 28, 1936, Serial No. 102,988

16 Claims. (Cl. 121—150)

My invention relates to expansible chamber motors, and more particularly to expansible chamber motors of the type especially adapted for pumping and similar uses. From one aspect, more specifically, my invention relates to improved distributing means for such motors, having automatic actuation and, super-imposed thereon, means permitting manual intervention, and the effecting of piston reciprocation with shortened strokes at times when full stroke operation may be impossible.

In the pumping of oil, it is very common to find sand in suspension in the oil, and the sand has a tendency to remain in the pump cylinder and gradually to increase in quantity therein to such a degree as to slow down the operation of the pumping motor, and then, if conditions are not remedied, to interrupt the operation of the pumping motor completely, necessitating pulling out of the pump. I have found it possible, by providing means whereby the stroke of the pumping motor may be shortened and the apparatus made entirely independent of the automatic control of the distributing devices thereof, to clear out the sand from the pump cylinder and enable operation to be resumed. In a preferred form of the invention, in which a pump-operating motor having a fluid actuated distributing valve is employed, I provide means operable under manual control whereby the normal movement of the pump-operating motor piston necessary to effect admission or venting of fluid, to effect valve throwing, need not take place in order for the direction of piston movement to be reversed. Preferably I provide means whereby both strokes of the motor piston may be shortened, that is to say, means whereby the motor piston may be caused to reciprocate with a short stroke between points lower than its normal upper limit and above its normal lower limit of movement. By the provision of such means, an unsanding operation can be most effectually accomplished.

It is an object of my invention to provide an improved expansible-chamber motor having means associated therewith whereby the unsanding of a pump operated thereby may be effected. It is another object of my invention to provide an improved expansible-chamber motor having automatic fluid distribution means and supplemental means whereby the motor may be relieved of said automatic control and caused to follow a cycle absolutely such as the operator may desire. It is a further object of my invention to provide an improved expansible-chamber

motor having automatic fluid distribution means of the fluid-actuated type, controlled by movement of the piston within the motor cylinder and having auxiliary, selectively operable means whereby the full length travel of the piston may be made unnecessary in order to effect the reversal of the positions of the fluid-distributing valve. It is yet another object of my invention to provide an improved form of manual controlling apparatus adapted to exercise a super- 10 seding control over the fluid distribution valve of a pumping motor, and to make the said valve directly responsive to manual manipulation of the controlling means provided, and independent of piston travel to the points which normally 15 determine valve throwing. Other objects and advantages of the invention will hereinafter more fully appear.

In the accompanying drawings, in which, for purposes of illustration, one illustrative embodiment of my invention has been shown:

Fig. 1 is a front elevation of a pumping motor in which my invention is incorporated in an illustrative form.

Fig. 2 is a sectional view, a portion of the 25 section, that through the pumping cylinder, being taken upon the section line 2—2 of Fig. 1, and the section through the distributing valve proper being a section at right angles to the plane of the line 2—2.

Fig. 3 is an enlarged, fragmentary, sectional view, showing details of the distributing valve mechanism shown in Fig. 2.

Fig. 4 is a view through the distributing valve mechanism, similar to a portion of Fig. 2, showing the distributing valve in a different position.

Figs. 5 and 6 are diagrammatic views showing supplemental control valves, and the different positions thereof for shortening the upward and downward piston travels respectively.

Referring to the drawings, and first to Fig. 1 thereof, it will be observed that a suitable support, a fragment of which is shown at 2, is adapted to support a pumping motor, generally designated 3. The motor 3 includes an upper head 4, a lower head 5, and an elongated cylinder 6 which may be formed in one piece or in a plurality of aligned parts, as desired. Suitable tension elements 6a connect the upper and lower heads 4 and 5, and clamp the cylinder 6 between these heads. Cylinder 6 has a bore 7 in which the motor piston 8 is reciprocable. Piston 8 has connected to it a piston rod 9 which extends through a suitable packing 10 and is adapted to actuate through an appropriate 55

sucker rod line, not shown, a lift pump at the bottom of the well.

Piston 8 is single acting, and pressure admitted beneath the same raises it; and its downward movements are caused by its own weight and by that of the connected parts, when a reduction in pressure beneath the piston takes place. The lower end or head of the motor cylinder has therein a fluid supply groove 13 to 10 which motive fluid at an appropriate pressure, say 200 to 300 pounds per square inch, may be admitted through a fluid supply connection 14. Spaced materially below the supply groove 13 is an exhaust groove 15, which is connected to 15 an exhaust connection 16. Between the grooves 13 and 15 is another groove 17 which is connected by a passage 18 to the space beneath the piston 8 in the cylinder 7. Desirably the motor operates with back pressure, and the back pressure is predetermined in such a manner as to provide the necessary retardation of the motor piston 8 and its suspended parts during the down-strokes thereof. The upper end of the motor cylinder is provided with an appropriately 20 vent-valve-controlled connection with the atmosphere, the vent-valve control device being designated 19 and being operative to provide for breathing of the upper end of the cylinder during normal motor operations, but cushioning and 25 checking the motor piston travel in the event of breakage of the sucker rod line, the blowing through of a pump packing, or the like.

A suitable, cylindrical, sleeve-like member 21 is received in a stepped bore 22 in the lower cylinder head 5, and is provided with aligned internal bores 23 and 24, the latter being the longer and the smaller in diameter. The bore 24 extends for the full length of the portion of the sleeve 21 which is opposite the spaces 13, 15 and 17; and 25 ports 25 connect the bore 24 with the space or groove 13, while ports 26 connect the space or groove 15 with the bore 24; and the annular groove 17 is connected with the bore 24 as at 27. A lower head 28, having a reduced portion 29, is appropriately held to the bottom of cylinder head member 5, opposite, and closing the bore 22; and its reduced portion 29 fits into and closes the lower end of the bore 24. As the sleeve 21 is not a close fit for the lowermost portion of 30 the bore 22, and as a passage 30 is provided connecting said lowermost portion of said bore with the bottom of the bore 24, the lower end of the bore 24 is continuously maintained at the same pressure that prevails in the groove 15, to-wit: 35 motor back pressure. Within the bores 23 and 24 there is reciprocable a suitable fluid-distribution valve 32, said valve including an upper, larger, ringed head 33 fitting the bore 23, an intermediate, doubly-ringed head 34 fitting the bore 24, and a lower ringed head of the same 40 diameter as the head 34, also fitting bore 24 and designated 35. Reduced portions 36 and 37 respectively connect the heads 33 and 34 and the heads 34 and 35. A fluid-conducting groove 38 surrounds the portion 37.

Obviously the motor back pressure acting continuously on the lower end of head 35 would maintain the distributing valve 32 in raised position (the position shown in Fig. 4) unless a pressure sufficient to move the valve downward were exerted upon the upper end of the head 33. For the purpose of periodically exerting such a pressure upon said head, and of venting the same at desired times, I have provided the means which 45 I shall now describe. The upper end of the

member 21 is closed by a suitably secured head 40. Arranged centrally in the head 40 is a tubular member 41 having an enlarged portion 42 at its lower end which provides a valve seat 43 surrounding the mouth of a passage 44. The upper end of the distributing valve 32 provides a yielding mounting for a valve element 46 having a tapered, seat-engaging portion 47 adapted to contact with the stationary seat 43 and close off communication between the passage 44 and the space, 50 herein designated for convenience 48, above the valve head 33. The passage 44 is connected by appropriate tubing and controlling devices, hereinafter more fully described and generally designated 59, to a point of communication 51 with the cylinder bore 7 adjacent the position occupied by the upper end of the motor piston 8 near the end of the downstroke of the latter, a position in which it is desired to shift the reciprocating distributing valve 32 to cause admission, 55 for the purpose of effecting a new working stroke.

The reciprocation of the distributing valve 32 is maintained truly rectilinear and rotation of said valve about its axis is prevented, by a guide rod 53 fixed in the head 40, and a cooperating 60 guide bore 54 formed in the valve proper.

A hardened contact 55 is mounted in the upper end of the distributing valve 32, which may very desirably be made of aluminum or other light material; and this contact is adapted to engage 65 the stem 56 of a spring-pressed valve member 57, which is normally maintained by a spring 58 upon a seat 59 carried by the head 40. The valve 57 is ported as at 60, and when it is unseated by pressure against its stem by the contact element 60 55, there is opened a passage between the space 61 above the valve and the space 48 above the distributing valve head 33, through an annular space 63 surrounding the stem 56 and through the passages 60. The space 61 is connected by suitable passage and controlling means, hereinafter more fully described and generally designated 65, with a point of communication 66 with the cylinder bore 7, adjacent a point in the latter which is uncovered by the lower end of the 70 upwardly moving motor piston as said motor piston approaches the desired upper limit of its stroke.

Disregarding, for the present, the special controlling means provided as parts of the structures 59 and 65 hereinabove mentioned, the mode of operation of this device would be as follows: In the position of the distributing valve shown in Fig. 4, pressure fluid would be admitted from the groove 13 through the space 38 surrounding the reduced portion 37 to the groove 17, and through the passage 18 into the cylinder bore beneath the piston 8. Piston 8 then begins to move upward, and as it moves upward its lower end first passes above the point of communication 60 51. Motor fluid from the cylinder bore at working pressure of 200 to 300 pounds, approximately, then passes into the connection 44, but since the valve 47 is upon the seat 43, the fluid within the passage 44 cannot attain access to the space 65 48, and, therefore, the distributing valve remains in its uppermost position. The motion of the motor piston 8 therefore continues upwardly, and the motor piston finally attains a position where its lower end passes above the communication 70 point 66, and thereupon pressure fluid passes through the connection etc. 65 into the space 61, through the ports 60 and the annular space 63 and into the space 48, and starts down the fluid distributing valve 32, as the latter will then 75

be subjected to inlet pressure upon its larger end 33 while its smaller lower end is still subjected only to motor back pressure. Downward valve movement will be completed by pressure through passage 44. This causes interruption of motor fluid supply beneath the motor piston 8 and a connection of the groove 17 in communication with the lower end of the motor cylinder with the exhaust groove 15, and so exhaust takes place. As exhaust takes place, of course, the pressure in the space 48 is reduced, but this pressure is not reduced sufficiently to cause the distributing valve to resume the position of Fig. 4, this being due to the fact that the reduction in pressure at this time can never be below that pressure which constantly prevails in the lower end of the bore 24, and since the head 33 is larger than the head 35 the distributing valve will remain in the position of Fig. 2. However, the pressure within the motor cylinder will fall sufficiently so that the weight of the piston, piston rod, the rod line etc., will cause downward movement at an appropriate rate, of these parts. As soon as the upper end of the motor piston 8 passes below the connection point 66, there will be a venting of the space above the valve 57 to atmosphere, for the upper end of the motor cylinder is connected to atmosphere through the relief device 19. However, the pressure within the space 48 will not be vented to atmosphere, as the valve 57 is held to its seat 59 so firmly by the spring 58 that it cannot be unseated by the pressure then within the space 48. Accordingly the motor piston will continue its downward movement until its upper end passes below the point of communication 51, and at that moment there will occur an escape of the pressure from within the chamber 48, since, in the position of the distributing valve of Fig. 2, which has been the position of said valve during the downstroke of the motor piston, the valve 47 is not resting upon the valve seat 43. It may be noted in passing that as soon as the valve 32 assumes its lower position, that shown in Figs. 2 and 3, the valve 57 assumes a seated position which it maintains until the upward movement of the distributing valve causes the contact 55 to engage the stem 56 and unseat the valve 57. It may be noted, moreover, that when the distributing valve assumes its uppermost position, the valve surface 47 seats upon the seat 43 and maintains the passage 44 sealed until fluid admitted past the valve 57 forces down the distributing valve, and thereby causes an opening of the communication between the passage 44 and the space 48.

We have now traced a complete cycle of the pumping motor, and under normal conditions this cycle of operations would be continued indefinitely, provided a suitable back pressure were maintained and provided motor fluid at a suitable supply pressure were continued to be provided. However, due to the frequent presence in the oil of sand, as above pointed out, it is possible that the sand taken into the pump cylinder will ultimately interfere so markedly with the operation of the pump plunger, that the motor piston 8 will not be able to maintain normal operation. Obviously the motor will not stop immediately, with this apparatus, though it will slow down and may also operate with reduced stroke. Ultimately, however, actual interruption of the operation might be possible, but even then the present apparatus would preclude damage to the sucker rod line such as would be occasioned were

some other forms of power supplied for the reciprocation of the pump plunger. For example, if a working-beam type of pump were being employed, and with the excess power which these devices normally have, if the pump sanded up 5 there would promptly be an elongation of the sucker rod line, which would ruin the same quite promptly.

Means is provided in the mechanism herein disclosed for the purpose of permitting the unsanding of the pump by churning the piston thereof up and down in such a manner as to get the sand in the pump cylinder into suspension and enable its discharge. Figs. 5 and 6 diagrammatically illustrate this mechanism. In these 15 figures, 66 represents, as in Fig. 1, the upper point of communication with the cylinder bore and 65 represents the connection with space 61 above the valve 57. A three-way valve mechanism, including a casing 70, having therein a 20 hollow rotary valve 71 providing diametrically opposite ports 72 and 73 and a right-angularly arranged port 74, and having an operating handle 75, is adapted selectively to connect a space 76, in communication with the communication 25 point 66, and a space 77, in communication with the connection 65, or to connect the space 77 through the ports 72 and 74 in the valve with another space 78, which is connected as at 79 with a point 80 in the cylinder bore which is 30 uncovered quite early in the normal upward stroke of the motor piston 8.

Before describing the mode of operation of this auxiliary control device, the structure of the control device associated with the passage 44 35 will also be described. Referring to Fig. 5 again, it will be noted that the point of communication 51 is connected with a three-way valve mechanism generally designated 82, and comprising a casing having chambers 83, 84 and 85 therein, 40 chamber 83 being in communication with the point 51, chamber 84 being connected with the passage 44, and chamber 85 communicating with the atmosphere. The valve mechanism 82 includes a hollow rotary valve 86, having diametrically opposite ports 88 and 89 and a right-angularly arranged port 87. In the position of the device shown in Fig. 6, i. e. with the operating handle 90 in a horizontal position, the passage 44 communicates with the atmosphere. With 50 45 the handle 90 vertical, as in Fig. 5, the passage 44 is placed in communication with the point 51 in the cylinder through the mutually opposite ports 88 and 89.

Now let us imagine that the pump is sanded up 55 and that it is necessary to get the sand out of the pump. It will be possible, of course, simply to effect downward movement of the valve 32 when the upward piston stroke stops, or possible to operate the motor with considerably shorter 60 strokes, and more rapid strokes, and thereby churn up the sand in the pump cylinder and clear out the pump cylinder much more promptly. As this latter method is more conducive to an early resumption of normal pumping operations, 65 this will be described at this point. Assume the distributing valve 32 to be in the position shown in Fig. 4, and that admission is taking place to the cylinder from the supply-connected groove 13 through the space 38 and the passage 18 leading to the lower end of the motor cylinder: the pump motor piston 8 will then be moving upwardly, and as soon as the lower end of the pump motor piston 8 has passed above the connection point 51, cylinder pressure which then exists 75

within the connection 79 and the space 78 can, if the operator moves the handle 75 into the position shown in Fig. 5, be caused to pass through the port 73 to the interior of the valve 71, through the port 74, space 77, and connection 65, and through passages 60 and 63; and the distributing valve will be moved down to the position shown in Fig. 2, its downward movement completed as usual by pressure through passage 44; and the motor piston will not complete its normal upstroke. Now, moreover, it will not be necessary to allow the motor piston to travel all the way down to its normal lowest position before its motion can be again reversed, and if the controlling handle 90 be moved into the position shown in Fig. 6, the distributing valve 32 will move at once from the position shown in Fig. 2 back to the position shown in Fig. 4, for the pressure holding the distributing valve in the position of Fig. 2 will be immediately vented to atmosphere, through the passage 44, chamber 84, port 87, and the hollow interior of the valve 86, port 89, chamber 85, and the atmospheric connection.

Now it will be evident, since the distributing valve 32 effects motor exhaust in its lower position and since said distributing valve may be caused to move from its lower position to its upper position merely by shifting the control handle 90 to the position thereof shown in Fig. 6, that the extent of downward movement of the motor piston may be made just about as small as desired; and the upward strokes of the motor piston may also be made very short by moving the control lever 75 to the position shown in Fig. 5. It may be said that between the connection points 51 and 66, long or short piston strokes may be effected, the length of the upstroke determined merely by selecting the time to throw the handle 75 to the position of Fig. 5, and the downstrokes being terminable at will by throwing handle 90 to the position of Fig. 6. All that is necessary to obtain a normal operation of the pumping motor is to turn the two levers 75 and 90 to the positions shown in Fig. 1, and to leave them there, in which event the motor will operate upon its normal cycle with long strokes, and upon a rectangular cycle. It will be understood that during short-stroke operation the handles 75 and 90 need to be thrown down horizontally only momentarily, and each is best thrown down only when the other is substantially vertical.

From the foregoing description it will be apparent that I have provided an improved arrangement including an automatic distributing valve means, and means for manually rendering the automatic operation of said distributing valve means inoperative and permitting the effecting of the events of cut-off and admission almost absolutely at the will of the operator. It will be evident that the operator can stand at the two control handles 75 and 90 and control the upward and downward movements of the motor piston in such manner as to cause a rapid surging upwardly and downwardly of the pump piston, and thereby force into suspension the sand within the pumping cylinder and effect a discharge of that sand with the liquid within the pump. It will be evident that the structure is simple, and that it is not subject to easy derangement; and that it permits not only unsanding but a testing of the motor operation in a very advantageous manner. It will further be noted, bearing in mind the comparatively small number of strokes per minute of the motor disclosed,

that the improved control means described permits controlling the individual strokes of the motor, that is, each individual stroke can be individually controlled as desired within the limits above noted; and control of any selected stroke or strokes is possible, as well as control substantially irrespective of the position of the motor piston in the cylinder; and control at will of venting of the valve throwing pressure by manual operation of handle 90 is independent of the usual automatic piston control.

While in the foregoing description I have described, and in the accompanying drawings illustrated, one embodiment which my invention may assume in practice, it will be understood that said invention may assume many other forms and be modified without departing from the spirit thereof, or the scope of the appended claims.

What I claim and desire to secure by Letters Patent is:

1. In combination, a motor cylinder, a piston normally reciprocable therein in a predetermined path, a distributing valve for said motor, fluid pressure throwing means for throwing said distributing valve on each stroke of the piston in said predetermined path and governed by piston movement, and means for effecting under manual control upon any selected stroke of the piston, throwing of said distributing valve at any time prior to the attainment by said motor piston to the normal valve throwing positions thereof.

2. In combination, in a motor, a cylinder, a piston reciprocable therein, a fluid-actuated distributing valve for said motor, means for subjecting one end of said distributing valve continuously to pressure, means controlled by said motor piston for alternatively subjecting the opposite end of said distributing valve to cylinder pressure and venting pressure therefrom, said valve thrown in one direction by the subjecting of said opposite end of said valve to cylinder pressure, and in the other direction by a venting of pressure acting upon said opposite end of said valve, and means under manual control and operative during any selected cycle or cycles of said piston, for effecting such subjecting and such venting prior to the attainment of said motor piston to the respective positions thereof at which such subjecting and such venting normally occur in the regular operating cycle of said motor.

3. In combination, in a motor, a cylinder having one end thereof constantly connected to atmosphere, a piston in said cylinder, and means for alternatively subjecting the end of said motor piston more remote from said cylinder end alternatively to live pressure or to a back pressure materially in excess of atmospheric pressure, including a distributing valve having one end thereof constantly subjected to motor back pressure and having means for subjecting the other end thereof alternatively to the pressures at the opposite sides of said motor piston, and means operative under manual control for connecting the last mentioned end of said valve to atmospheric pressure, or to live pressure, substantially irrespective of the position of the motor piston within said cylinder.

4. In combination, in a pumping motor, an upright cylinder, a single acting piston reciprocable therein, a fluid distributing valve for alternatively admitting motive fluid beneath said motor piston and connecting the space beneath said motor piston to exhaust, means for subjecting one end of said distributing valve continu-

ously to a pressure above atmospheric pressure, and means for alternatively subjecting the other end of said valve to atmospheric pressure or to pressure conditions within said motor cylinder beneath said motor piston, including passages leading from said last mentioned end of said valve to spaced points in the motor cylinder and valves controlling said passages and respectively carried by and actuated by said fluid distributing valve, and means under operator control for subjecting said distributing valve through portions of said passages to cylinder pressure or to atmospheric pressure prior to the attainment by said piston to the respective points of piston movement at which such connections are normally effected.

5. In combination, in a motor, a cylinder disposed at an angle with the horizontal and having a single acting piston reciprocable therein, fluid distribution means for alternatively admitting live pressure to and exhausting pressure from said cylinder beneath said piston, said distribution means including a reciprocatory distributing valve having one end thereof constantly subjected to motor back pressure and having means for subjecting the other end thereof alternatively to atmospheric pressure through the upper end of said motor cylinder and to pressure conditions beneath said motor piston, said means for subjecting including a pair of passages, one connecting the space above said valve with a point in said motor cylinder uncovered by the lower end of the upwardly moving motor piston comparatively late in the working stroke thereof, and the other connected with a point in the motor cylinder uncovered by the downwardly moving motor piston at a point comparatively late in the downward stroke thereof, and means under manual control for alternatively subjecting the upper end of said distributing valve to the pressure in the cylinder beneath the motor piston and to atmospheric pressure through the upper end of said motor cylinder and through a direct atmospheric connection respectively, at will.

6. In combination, a vertically-disposed motor cylinder, having therein a motor piston, a fluid distributing valve reciprocable parallel to said motor piston and having the lower end thereof subjected continuously to motor back pressure, means for alternatively subjecting the upper end thereof to atmospheric pressure through the non-working end of said motor cylinder and to pressure conditions within said cylinder beneath said motor piston, including a pair of passages, one controlled by a valve carried by said distributing valve and connected to said motor cylinder at a point uncovered by the lower end of the upwardly moving piston comparatively early in the working stroke of said motor, and another controlled by a valve moved to open position by said distributing valve when the latter is positioned to admit fluid to said cylinder, the last-mentioned passage communicating with the motor cylinder at a point uncovered by the lower end of the upwardly moving piston comparatively late in the working stroke thereof, and means under operator control for connecting said last mentioned passage with said motor cylinder at a point uncovered by the lower end of the upwardly moving motor piston comparatively early in the working stroke thereof, and means for connecting said first mentioned passage directly with atmosphere, at will.

7. In combination, in a pump operating motor,

a cylinder, a piston reciprocable therein, and fluid distribution means for said motor including a valve movable in opposite directions between admission and exhaust positions, means for continuously subjecting one end of said valve to a pressure in excess of atmospheric pressure, tending to move said valve to admission position, and means for selectively subjecting the other end of said valve alternately to the pressure within said motor cylinder beneath said piston and to atmospheric pressure through the non-working end of said cylinder, to cause reciprocation of said valve, including two passages, one of said passages extending from a point uncovered by the lower end of the motor piston early in the working stroke thereof and having a controlling valve therefor carried by said distributing valve, the other of said passages uncovered by the lower end of the upwardly moving piston comparatively late in the working stroke thereof, and having a controlling valve unseated by the fluid distributing valve when the latter is in fluid admission position, and means for short-stroking said motor including means under manual control and arranged in said first mentioned passage for effecting a direct communication of said passage to the atmosphere irrespective of motor piston position, and means under manual control associated with said second mentioned passage for placing the same at will in communication with said motor cylinder at a point uncovered by the lower end of the motor piston early in the normal upward travel thereof.

8. In combination, a motor cylinder, a piston reciprocable therein, a distributing valve for said motor, fluid pressure throwing means for said valve operative to effect cutoff or admission when the motor piston attains to predetermined positions in its strokes, and means including cylinder connections under manual control for controlling the individual strokes of said motor and manipulable to cause cutoff or admission by said valve at any time prior to attainment by said piston to said positions.

9. In combination, a motor cylinder, a piston reciprocable therein, a distributing valve for said motor, fluid pressure throwing means for said valve controlled by said piston and operative to effect admission upon the attainment to a predetermined position in its non-working stroke by said motor piston, and means under manual control for controlling the individual strokes of said motor and manipulable to cause admission by said valve at any time prior to attainment by said piston to such position upon but a single stroke, if desired.

10. In combination, a motor cylinder, a piston reciprocable therein, a distributing valve for said motor, means controlled by the motor piston at predetermined positions of the latter for effecting valve throwing on each piston stroke, and means operative under manual control after piston movement starts for a given stroke to effect valve throwing at any time prior to the moment when the piston attains to one of such positions on such stroke.

11. In combination, a motor cylinder, a piston reciprocable therein, a distributing valve for said motor, means controlled by the motor piston at predetermined positions of the latter for effecting valve throwing on each piston stroke, and means operative under manual control and actuatable between the times when the motor starts towards and reaches one of such positions, to effect pressure fluid valve throwing at any time

- prior to the moment when the piston attains to such position.
12. In combination, a motor cylinder, a piston reciprocable therein, a distributing valve for said motor, means controlled by the motor piston upon attainment of the latter, on each stroke thereof in a given direction, to a predetermined position for effecting valve throwing, and means operative under manual control, and including a cylinder connection beyond which said piston has moved before said last mentioned means is actuated to render it effective, to effect cylinder pressure effected valve throwing irrespective of piston position, prior to the moment when the piston attains to said predetermined position.
13. In combination, a motor cylinder, a piston reciprocable therein, distributing valve means for said motor, fluid pressure throwing means for throwing said distributing valve on each piston stroke and governed by piston movement, and manually operable means for effecting throwing of said distributing valve by fluid pressure irrespective of piston position, thereby controlling said valve means to provide for substantially any stroke between full stroke and a stroke a small fraction of full stroke.
14. In combination, a motor cylinder, a piston reciprocable therein, a distributing valve for said motor, controlling means for said valve operative to effect throwing thereof under piston con-

trolled fluid supply and venting, and means for effecting at will the venting independently of piston control.

15. In a motor, in combination, a cylinder, a piston reciprocable therein, a distributing valve for said motor controlling admission of working fluid thereto, controlling means for said distributing valve including a pressure area acting to move said valve to open position, means for conducting pressure fluid to said area and venting pressure therefrom including connections to said cylinder, valves for controlling said connections and respectively actuated by and carried by said distributing valve, and manually operable means for controlling the connections of said pressure fluid conducting means to said cylinder.

16. In combination, a motor cylinder, a piston reciprocable therein, a distributing valve for said motor, throwing means for said valve rendered effective on venting of said distributing valve to atmosphere and operative to effect admission upon the attainment to a predetermined position in its non-working stroke by said motor piston, and means under manual control for venting said distributing valve to atmosphere at any time during the non-working stroke of said motor piston prior to attainment by said piston to such position.

WADE H. WINEMAN. 30
